UNITED STATES PATENT OFFICE.

JOHN T. SLOCOMB, OF CRANSTON, RHODE ISLAND, ASSIGNOR TO ECONOMY COOKER COMPANY, OF EAST PROVIDENCE, RHODE ISLAND, A CORPORATION OF RHODE ISLAND.

STEAM-PRESSURE COOKER.

Application filed August 24, 1921. Serial No. 495,071.

To all whom it may concern:

Be it known that I, JOHN T. SLOCOMB, a citizen of the United States, residing at Cranston, in the county of Providence and State of Rhode Island, have invented certain new and useful Improvements in Steam-Pressure Cookers, of which the following is a specification.

My invention relates to those steam cookers wherein the steam is retained under pressure, and more particularly to the closures thereof.

The essential objects of my invention are the prevention of cramping in the application or removal of the cover; the protection of the grooved seat of the cover against bending when accidentally dropped or struck; to enable an automatic tightening or loosening of the cover while in or out of use respectively; to facilitate the centering of the cover upon the body while being applied; to strengthen the top of the boiler body; and to attain these ends in an inexpensive structure.

To the enumerated ends essentially my invention consists in such parts and in such combinations of parts as fall within the scope of the appended claims.

In the accompanying drawings which form a part of this specification,

Figure 1 is a side elevation of a boiler in which my invention is incorporated,

Figure 2, a transverse central section of the same enlarged, and

Figure 3, an enlarged fragmentary section of the cover and of the boiler body on a line corresponding to that of Figure 2.

Like reference characters indicate like parts throughout the views.

In the drawings 5 represents the side wall of a steam pressure cooker body of any usual preferred construction provided with lateral sockets 7 to pivotally receive the heads or ends 8 of the resilient yoke or bail 9 provided with a central cavity 10.

The body wall 5 is preferably composed of Monel metal and is in this case cylindrical in outline. The upper portion of the wall 5 as at 12 is of increased thickness to sustain the strain of the yoke. The top of the body has an upwardly and inwardly inclined beveled margin 13 upon its outer face, an upwardly and an outwardly inclined beveled inner margin 14, the latter being formed on an internal annular shoulder 15. The

marginal faces, therefore, if extended would converge.

The cover or closure member comprises a top or body portion 17 having in this instance a socket 18 for a sleeve 19 adjustable by a screw 20 and threaded to a post 21 whose end registers in the cavity 10. The post carries a cross bar 23. The body 17 of the cover is provided with a laterally extending rounded peripheral shoulder 25 merging into a rounded depending interiorly inclined shoulder 26. Depending from the body 17 inside the shoulder 26 is an annular lug 28 spaced at its top from the shoulder 26 by an annular recess 30, and projecting below the shoulder 26, and provided with a rounded lower extremity, as at 31. The exterior face of the lug 28 is inwardly inclined or beveled, and is adapted to rest against the beveled face 14 of the vessel body. The rounded or inclined lower inner face of the shoulder 26 is adapted to engage the inclined face 13 of the body portion 15 whose upper edge is adapted to enter the recess 30. The material is preferably aluminum.

The exponent of expansion of Monel metal is less than that of aluminum, and this difference of degree of expansion of the two metals causes the cover to adhere to the body of the cooking utensil more tightly during the cooking period.

The annular shoulder 25 is a protection to the channel 30 as the cover is dropped upon its edge, and the member 28 performs a like function when the cover is dropped horizontally. The downward extension of the member 28 below the shoulder 26 serves as an auxiliary guide and centering means for the application of the cover. It is desirable that the shoulder 26 and the lug 28 be used in order to assure a sufficient strength to withstand the great pressure brought to bear in this class of articles. Mere flanges would not be sufficient for this purpose.

As will be readily understood from Figure 3, there is an annular clearance space provided by the annular recess 30 which insures that the cover will properly wedge to the sloping sides of the cooker seat.

I claim:-

1. In a steam pressure cooker, a cooker body, a cover comprising a top, a lateral rounded shoulder upon the top, a rounded depending shoulder integral with the first shoulder, a depending annular lug provided

with a rounded end and depending from the top to a point below the second shoulder and spaced from the second shoulder to admit the cooker body therebetween, the parts forming means for wedgingly pinching the cover and body together.

2. In a steam pressure cooker, a body having beveled cover receiving portions and formed of Monel metal, and an aluminum cover comprising an annular depending shoulder and an adjacent depending lug spaced from each other and forming a space to receive the cover receiving portion of the body.

3. In a steam pressure cooker, a body having beveled cover receiving portions, a cover

comprising an annular shoulder and an annular lug spaced from each other to receive the body therebetween, said body and cover being composed of metals having different degrees of expansion by heat.

4. In a steam cooker, a body having upwardly and oppositely inclined beveled faces, and a cover having an annular recess correspondingly tapered to receive said beveled faces of the body and to leave a clearance space above the upper edge of the beveled portion of the body.

In testimony whereof I have affixed my signature.

JOHN T. SLOCOMB.
